UNITED STATES PATENT OFFICE.

WILLIAM E. McLAREN, OF CHICAGO, ILLINOIS.

CONVERTIBLE HIGH CHAIR.

1,299,366.

Specification of Letters Patent.

Patented Apr. 1, 1919.

Application filed June 28, 1918. Serial No. 242,333.

To all whom it may concern:

Be it known that I, WILLIAM E. McLAREN, a citizen of the United States, and a resident of Chicago, in the county of Cook and State 5 of Illinois, have invented certain new and useful Improvements in Convertible High Chairs, of which the following is a specification.

This invention relates to improvements in 10 a convertible article which may be used practically for the service of children, or if desired, so that it can be employed by them as a toy, or in play, and it consists in certain 15 peculiarities of the construction, novel arrangement and operation of the various parts thereof as will be hereinafter more fully set forth and specifically claimed.

The principal object of the invention is to 20 provide a highly useful household article, which shall be simple and inexpensive in construction, strong, durable, and efficient in operation, which can be used practically as a high chair, a bassinet or cradle, or a cage or keeper for children, from one to another 25 of which devices it can be readily and quickly converted, or if desired, it can be constructed, of proper size and material, and be used by children as a toy for dolls, in which event, the same construction and convertibility will be maintained. Another important object is the provision of an article 30 of the above named general character which can be constructed almost, if not entirely, of wooden parts, thereby eliminating the expense of metallic parts. A further object 35 is to so arrange and combine parts of the device that certain fastening means thereof will perform several functions without any alterations therein, but by simply changing 40 their positions. Various other objects and advantages of the invention will be disclosed in the subjoined description and explanation.

In the accompanying drawings which 45 serve to illustrate the invention,

Figure 1 is a rear perspective view of the device showing the parts in the positions they may be caused to occupy when the device is to be used as a high chair.

Fig. 2 is a side view of the device showing 50 its parts by continuous lines arranged for its use as a trundling keeper or cage and by dotted lines as a bassinet or cradle.

Fig. 3 is a cross sectional view taken on 55 line 3—3 of Fig. 2 looking in the direction indicated by the arrows.

Fig. 4 is an enlarged fragmental sectional view taken on line 4—4 of Fig. 1 looking in the direction indicated by the arrows showing means for supporting and holding the 60 platform or table portion of the high chair in its horizontal position, and

Fig. 5 is a fragmental view taken on line 5—5 of Fig. 3 looking in the direction indicated by the arrows showing by full lines 65 one of the rockers of the cradle held in operative position and by dotted lines the position in which it will be maintained when not in operative position.

Like numerals of reference refer to corresponding parts throughout the different views of the drawings.

The body of the device consists of a rectangular frame composed of two pairs 7 and 8 of side members or rails spaced apart 75 in parallelism with one another, so that when the device is used as a high chair said members will be located in an upright position, but when it is used as a keeper or cradle said members will be located in a horizontal 80 position as will be readily understood by reference to Figs. 2 and 3 of the drawings. These rails or members are united near one of their ends by means of bars or rails 9 which may be secured to said members in 85 any desired manner, but preferably by the use of wooden dowels 10 and as is clearly shown in Fig. 1 of the drawings in such a manner that the members 7 and 8 will be held at substantially equal distances apart 90 in the form of a rectangular figure. The opposite ends of the members 7 and 8 are connected at their front or upper portion and sides by means of bars or rails 11 which may also be held in place by means of dowels 95 10 as before mentioned and in such a way as to form three sides of a rectangular figure. Each of the bars or rails 11 is provided on its inner surface with a longitudinally extended ledge or flange 12, see Figs. 100 3 and 4, to support a platform 13 and a pivoted back or end piece 14 when in their folded positions. The members 7 and 8 are connected in pairs by transversely disposed rods or rungs 15 and similar rods or rungs 105 15 are employed to connect the front and rear or upper and lower rails 9 at the end of the device opposite the end members 13 and 14 above mentioned. The end piece or platform 13 is pivotally secured at its front 110 portion to the rails or bars 11 and by preference has its rear edge forwardly curved as

at 16, see Fig. 1 of the drawings, in which view it will be observed and understood that the member 13 can be turned upwardly on its pivot to permit a child to be seated on the seat 17 by passing its body through the frame composed of the rails 11 and the back or end piece 14 which is pivotally secured at its rear end to and between the upper portions of the rails 8 of the body of the device.

10 Fixed between the members 8 and extended from a point near the pivots 18 of the end piece or back 14 is a board 19 which extends at its other end to a point located at a considerable distance from the back 14. Near

15 the opposite ends of the members 8 on which the end piece or back 14 is mounted, a board 20 is secured to and between said members and in conjunction with the board 19 serves to strongly brace or connect said members

20 together. Pivotally mounted between the members 8 at a point near the inner end of the board 19 is the seat forming member 17 of the chair, which is of sufficient dimensions to close the opening between the inner

25 ends of the boards 19 and 20 and the rear or lower side rails or members 8 when it is desired to use the article as a bassinet or keeper. As shown in Figs. 1 and 3 of the drawings, each of the side rails or members

30 8 is provided on its inner surface with a ledge 21 on which the seat member 17 will rest when extended between the rails or members 8 in which position it can be held by means of a locking bar 22 which is pivotally mounted at its middle portion to the

35 lower or rear surface of the seat member 17 and has each of its ends provided with an extension 23 to overlap or engage the rear or lower surface of the members 8 as is shown by dotted lines in Fig. 1 of the drawings. When it is desired to use the device as a chair the seat member 17 can be released from the members or rails 8 by turning the locking bar 22 in the proper direction, when

40 it is obvious that the seat member 17 can be turned on its pivot so as to assume a horizontal position as shown by continuous lines in Fig. 1 of the drawings in which position it can be supported by means of the locking bar 22 which when turned to assume a parallel position with the front edge of the seat member 17 will overlap a pair of the rods 15 on the sides of the body and thus support said seat member. Journaled on each of the

45 rails or members 8 near each of its ends is a roller or wheel 24 the axles 25 of which may be of wood or metal as desired. Pivotally secured to the members or rails 8 between each pair of the wheels 24 is a rocker 26 each

50 of which has its end portions 27^a extended slightly outwardly of the rails or members 8 as is shown in different views of the drawings. Each of the rockers 26 has secured to its inner edge a cleat 27, see Figs. 1 and 5 of the drawings, which cleats are of suffi-

cient width to extend on each side of the rockers 26, thus forming a T-shaped base to rest against the floor or boards 19 and 20 when said rockers are placed in their operative positions as shown by dotted lines in Fig. 2 of the drawings and by continuous lines in Figs. 3 and 5 of the drawings. When in their operative positions, the bases 27 of the rockers may be engaged by the overlapping ends 28 of fastening buttons 29 one of which is secured to the rear or lower surface of the floor or boards 19 and 20 of the device. The rockers can be held in their inoperative positions, as shown by continuous lines in Figs. 1 and 2 of the drawings, by means of said buttons for it will be seen and understood in Figs. 1 and 5, that each of these buttons is provided at its ends with extensions 28 and 28^a, the extensions 28 being for the purpose of overlapping and engaging the bases 27 of the rockers when the latter are in their operative positions, and the extensions 28^a being for the purpose of contacting with the said bases when the rockers are in their inoperative positions.

From the foregoing and by reference to the drawings, it will be readily understood and clearly seen that when the device is used as a high chair, the end member 14 which forms a portion of the back of said chair can be raised from a horizontal position to a vertical position as shown in Fig. 1, when by turning the fastening button 29 so that its longer extension 28^a will engage the back 14 said back will be thereby held in its upright position. The seat member 17 can then be turned from its dotted line position as shown in Fig. 1, to that shown by continuous lines in said figure and held in its latter position by means of the bar 22 engaging the rods 15 on the body of the device, which bar can be manipulated as above set forth. In order to readily place the child in a sitting posture on the seat 17, the platform or table 13 may be turned upwardly on its pivot, thus opening the entire upper portion of the body. After the child has been seated in the chair, the platform 13 can be lowered, and if desired said platform can be provided at one or both of its side edges with a spring pressed bolt 30, see Fig. 4 which is adapted to engage a socket 31 seated in the inner surface of the rail 11 adjacent to said bolt. The spring 32 which actuates said bolt is located in a suitable opening 33 in the side edge of the platform 13 and will normally hold the bolt 30 in engagement with the socket 31, but on upward movement of the platform 13 will yield sufficiently to allow the disengagement of said bolt from its socket. If desired the end member or back 14 may be provided at one or both of its side edges with similar holding means for fastening said end member or back in position between the side rails 11 of the body of the device.

When the device is to be used as a bassinet or keeper the end members 13 and 14 should be closed and the seat member 17 released from its seat forming position and turned therefrom to the position shown by dotted lines in Fig. 1, in which position it can be locked by the bar 22 as above stated. When the parts are arranged as last above described it is apparent that the body of the article will have a sectional floor or bottom on which bed clothing can be placed if desired. It is also manifest that by adjusting the rockers to their operative positions and so fastening them, the device can be used as a rocking cradle, or if desired the rockers may be turned to their inoperative positions and there fastened, when the device can be used as a trundling or wheeled cage or keeper.

It is further obvious that by the improved, novel construction and arrangement of the various parts of the device, the fastening buttons and locking bar are each adapted to perform several functions without any alteration, but simply by changing their positions. While I do not desire to limit myself to the use of wooden parts for securing the various members of the device in position on the body thereof, yet it is obvious that wooden parts exclusively may be used, with the exception of the spring actuated bolt and its members, and that on account of the difficulty and expense of obtaining metal parts, at the present time, this is highly desirable.

Having thus fully described my invention what I claim as new and desire to secure by Letters Patent, is—

1. In a device of the class described, the combination with a frame having an opening extended from end to end thereof, of a sectional closure located opposite said opening, one of said sections pivotally mounted on the frame and adapted for movement therein, and means on said section to lock it to the frame in alinement with the other sections, and to engage the frame to support said section when extended into the frame.

2. In a device of the class described, the combination with a frame having an opening extended from end to end thereof, of a sectional closure located opposite said opening, one of said sections pivotally mounted on the frame and adapted for movement therein, and a bar pivotally mounted on said section to lock it to the frame when in alinement with the other sections and to engage parts of the frame to support said section thereon in a transverse position.

3. In a device of the class described, the combination with a rectangular frame having one of its sides open, of a sectional closure for the side opposite said opening, one

of said sections pivotally mounted on the frame and adapted for movement therein, means mounted on said section to lock it to the frame when in alinement with the other sections and to engage parts of the frame support said section in a transverse position, and a sectional closure for one end of the frame, at least one of said sections thereof being pivotally secured near one of its ends to the frame.

4. In a device of the class described, the combination with a rectangular frame having one of its sides open, of a sectional closure for the side opposite said opening, one of said sections pivotally mounted on the frame and adapted for movement therein, means mounted on said section to engage parts of the frame to support said section in a transverse position, a sectional closure for one end of the frame, one of said sections being pivotally secured near one of its ends to the frame and means carried by the frame to hold the last named pivoted section in a longitudinal position with respect to the frame.

5. In a device of the class described, the combination with a frame having an opening extended from end to end thereof, a closure located opposite said opening, a rocker transversely and pivotally mounted on the closed portion of the frame near each end thereof, each of said rockers having a flanged base on its edge adjacent to the closure, and a fastening button pivotally mounted on the closure near each end thereof and having extensions at its ends, one of said extensions adapted to engage flanges of said rockers to hold them in their operative positions and the other of said extensions adapted to abut against the flanges or bases of the rockers to hold them in their inoperative positions.

6. In a device of the class described, the combination with a rectangular frame adapted to be supported in an upright position, of a sectional closure for one of the walls of said frame, the intermediate section of said closure pivotally mounted on the frame and adapted for movement therein, means mounted on said section to engage parts of the frame to support said section in a transverse and horizontal position, a sectional closure for the upper end of the frame, each of said last named sections being pivotally secured near their opposite ends to the frame, and means carried by the frame to hold one of said pivoted sections in an upright position.
